LAP JOINT

Waldemar Kroier, Jacksonville, Fla.

Application September 30, 1937, Serial No. 166,664

2 Claims. (Cl. 108—18)

The invention relates to a lap joint for metal roofing and the method of making the same.

The primary object of the invention is the provision of a lap joint of this character, wherein in the metal roofing in the laying thereof can be lap jointed through nailing and crimping sheets together in a manner that the nails fastening the sheets will be concealed and avoiding the penetration of such nails through that portion of the sheet exposed to the weather elements and in this fashion effecting an anti-siphon, self-draining and blind nailed roofing to an edifice or the like.

Another object of the invention is the provision of a lap joint of this character, wherein the sectional sheathings involving the lap joint are removable and replaceable without in any way damaging the roofing with resultant leakage therethrough, the joint being effected in a novel manner so that the fasteners securing the sheathing to the roofing of a structure will be devoid of penetrations created by such fasteners, that is, that part of the sheathing exposed to the weather elements and a firm and secure lap joint is had without liability of the loosening of the sheathing or the roofing coming apart.

A further object of the invention is the provision of a lap joint of this character, wherein the sheathing sections can be interlocked or interfitted with each other and the fasteners securing such in place are concealed or blinded and the overlap joint effected with dispatch in the laying of the roofing or the separation of the sheathing for the mending of the roofing or the replacing of one section for another.

A still further object of the invention is the provision of a lap joint of this character, wherein a novel method is created in the laying of the sheathing for a roofing and in the lap jointing of the sections.

A still further object of the invention is the provision of a lap joint of this character, which is extremely simple in its construction, thoroughly reliable and efficient in operation, assuring a leakproof roof or other covering, strong, durable, assuring the laying of the roofing with dispatch and inexpensive to manufacture and install.

With these and other objects in view, the invention consists in the features of construction, combination and arrangement of parts as will be hereinafter more fully described, illustrated in the accompanying drawing, which discloses the preferred and modified forms of embodiment

of the invention and pointed out in the claims hereunto appended.

In the accompanying drawing:

Figure 1 is a fragmentary sectional view taken on the line 2—2 of Figure 2 looking in the direction of the arrows.

Figure 2 is a fragmentary top plan view of the lap joint constructed in accordance with the invention.

Figure 3 is a sectional view taken on the line 3—3 of Figure 2 looking in the direction of the arrows.

Figure 4 is a perspective view of a fastener for the lap joint having in association therewith a washer.

Figure 5 is a perspective view of a modified form of fastener.

Similar reference characters indicate corresponding parts throughout the several views in the drawing.

Referring to the drawing in detail, A designates generally a portion of the bed of a roof of a building or other edifice while B and C, respectively, denote portions of sheathing sections or metal roofing material covering such bed and preferably of sheet metal. These sections B and C in the laying thereof are joined by an overlap joint constituting the present invention and hereinafter fully described.

The overlap joint constituting the present invention is formed by distorting, in this instance, the section B linearly next to one longer edge thereof to effect upwardly disposed inverted V-shaped ridges or ribs 10 so that there exists between the same the substantially V-shaped channel or groove 11 while the section C is carried over these ribs or ridges 10 for a distance and such overhang of said section C has struck upwardly therefrom crownings 12 for the ridges or ribs 10 and these are in parallel spaced relation to each other in conformity with the separation of the ribs or ridges and each is flattened at 13 with a determined width between the side portions 14 of said crowning which are downwardly divergent and in this manner the ridges or ribs 10 in the section B are freely received in the crownings 12 at the overlaps of these sections with respect to each other.

Prior to the crowning of the ridges or ribs 10 or the overlapping of the section B by the section C, these ribs or ridges 10 at determined points have driven downwardly therethrough flat headed nails 15 which engage in the bed A securing the section B in place thereon, these nails 15 being passed through suitable holes 55

therefor in the ribs or ridges 10 and carry beneath the flat heads 16 substantially square or rectangular shaped concavo-convex washers 17, there being suitable loose play between the latter and the shanks or stems of the nails 15 for slight displacement or for free rotation of the washers 17 upon the nails.

The nails 15 are driven home sufficiently to bring the washers 17 thereon close to or in contact with the apexes with the ribs or ridges 10. Thereafter these ridges 10 with the nails 15 passed therethrough are overlapped by the crownings 12 in the section C and by depressing downwardly such crownings 12 the washers 17 in coaction therewith center the crownings in their interfitted relation to the ridges or ribs 10. Now in the use of a crimping tool, the sides 14 at the points confronting the nails 15 and the washers 17 can be pried upon by such tool for indenting or inwardly crimping of these sides 14 as at 18, being understood, of course, that pre-crimping of the crownings 12 can be had before lap jointing the sections B and C together. Thus the ribs or ridges 12 and the crowning 12 through the crimps 18 will be locked together in their interfitted lap jointed relation to each other and in this manner these sections B and C constitute the roofing.

When the crownings 12 are precrimped at 18, the lap jointing of the sections B and C is had by first permanently fixing the section B upon the bed A of the roof and then slidably interlocking the crownings 12 with the washers 17, the ribs or ridges 10 and the crownings 12 being disposed from the highest point or ridge of the roof to the lowermost edge thereof. In the creating of the overlap joint as heretofore set forth, the roof will be anti-siphoning, self-draining and blind nailed while the sections B and C are removable and replaceable with dispatch and ease.

In Figure 5 of the drawing there is shown a slight modification wherein the nail 19, which may be a substitute for the nail 15, is formed with a relatively large flat head 20 and in this instance the washer 17 can be dispensed with because this head 20 will interlock with the

crownings 12 in association with the crimps 18 in the sides 14 of such crownings as well as the flats 13 of the crownings, being clearly apparent from Figures 1 to 3 inclusive, of the drawing that no holes or openings in the roofing are exposed to 5 weather elements.

By reason of the formation of the overlap joint in the creation of the ridges or ribs 10 and the crownings 12 there is effected barriers due to spaces existing between said ridges and crownings for the checking of rain subjected to wind current forces to avoid seepage of such rain or the like into the joint to give entrance through the roof proper resultant in leakage there-through. In other words, the overlap joint constructed as hereinbefore set forth is positively leakproof.

What is claimed is:

1. A lap joint for sheathing comprising sheet-like sections superposed relative to each other at edges adjacent to one another for effecting an overlap therebetween, a crown struck outwardly from the outermost section at the overlap, a ridge struck outwardly from the innermost section at the overlap, a fastener passed through the ridge, and inwardly distorted portions at intervals in the outermost section at the overlap and at the point of said fastener for the locking of the crown and ridge together at the overlap, the fastening of these to a support and also entirely concealing the said fastener. 30

2. A lap joint for sheathing comprising sheet-like sections superposed relative to each other at edges adjacent to one another for effecting an overlap therebetween, a crown struck outwardly from the outermost section at the overlap, a ridge struck outwardly from the innermost section at the overlap, a fastener passed through the ridge, and inwardly distorted portions at intervals in the outermost section at the overlap and at the point of said fastener for the locking of the crown and ridge together at the overlap, the fastening of these to a support and also entirely concealing the said fastener, the crown being of greater width than the ridge. 40
